UNITED STATES PATENT OFFICE.

WILLIAM P. KING AND EMMETT T. CORBIN, OF HAMILTON, OHIO.

CEILING CONSTRUCTION.

Application filed May 5, 1927. Serial No. 188,958.

The present invention relates to an improved ceiling structure such as is used in concrete construction work for suspension of metal lathing.

5 Briefly, the invention has reference to a soffit form for pouring of a concrete joist construction which, in the present instance, embodies an especially constructed metal reinforcing means, a part of which forms a longitudinal stringer and suspension means for the backing rod and metal lathing which is tied thereto and suspended therefrom.

10 The principal feature is a novel stringer which is in the form of an insert plate in the form and which includes angularly disposed arms forming chairs for additional reinforcing members, together with depending suspension ears for the sealing structure.

15 A further feature of importance is an expansion tension hanger permitting the metal lathing to be suspended at the desired elevation from the concrete joists.

20 The particular physical features in the improved embodiment together with the advantages derived from their use, will become more readily apparent from the following description and drawings.

In the drawings:—

25 Figure 1 is a transverse section through the form into which the fluid concrete is poured.

30 Fig. 2 is a fragmentary top plan view of the same.

35 Fig. 3 is a cross section through the completed concrete joist, the embedded metal reinforcing means and a fragmentary portion of the metal lathing and suspension means.

40 Fig. 4 is an enlarged fragmentary detail perspective view of the improved reinforcing stringer and ceiling suspension inserts.

45 Fig. 5 is a detail perspective view of one of the extension hangers.

50 Fig. 6 is a view showing the hanger in place.

55 In the drawings, the reference character 7 designates generally the joist soffit form such as is used in form work for concrete joist construction. This includes the wooden soffit joist 8 located between the bottom portions of upstanding metal confining walls 9.

50 If desired, nails 10 may be driven into the longitudinal edges of the joist to provide stops for the lower ends of the walls 9. Located within this form is the novel metal insert and reinforcing device generally designated by the reference character 11. This device as better shown in Fig. 4, comprises a

strip 12 of an appropriate gage metal which is adapted to be inserted into the form in the manner shown in perpendicular position.

5 At longitudinally spaced points, arms 13 are struck out to provide elongated openings 14 on the bottom edge. These are preferably bent outwardly at right angles and are formed in staggered relation and constitute what may be conveniently designated as chairs providing seats for the reinforcing rods 15 and 16 respectively. Incidentally, the rod 15 is rectangular cross section, while the rod 16 is of cylindrical cross section.

10 In addition, this device is provided with depending suspension ears 17 which are located at equi-distant points, each one being of tapered configuration being provided in its bottom edge with a notch 18 and adjacent its top with a tie wire hole 19.

15 By directing attention to Fig. 3, it will be seen that the reference character 20 designates the completed concrete joist with the reinforcing insert and rod embedded therein. In this connection, it might be stated that when 20 this device 11 is set in position in form, the ears 17 is driven down into the wooden joist 8 or if desired, the joist may be provided with sockets of these. When the product is finished, the ear 17 extends or projects below the bottom of the joist as shown in Fig. 3, and also as represented here, the reference character 21 designates the ceiling lathing of ordinary form, which is clamped against the metal backing rod 22.

25 These rods are located in the notches 18 and the parts are assembled by a tie wire 23. The wire is passed through openings in the ceiling material and through the aforesaid holes 19. This obviously maintains the 30 parts in assembled relation firmly.

35 In some instances, it is desired to suspend the ceiling structure further down from the concrete joist, and this is preferably done by employing extension hangers, one of which 40 is shown in Fig. 5, and designated by the reference character 24. The hanger comprises a small metal strap having a hook 25 at its upper end and having laterally bent shoulders 26 intermediate its ends.

45 The intermediate portion of the shank 27 is twisted and the shank terminates in a bent-up rod receiving seat, which operates in the manner represented in Fig. 6. Obviously, when this hanger is used, the hook 25 is 50 placed through the hole 19 in the depending ear 17 while the shoulders 26 come beneath

the lower end of the ear. Thus a dependable extension hanger is provided.

It is believed that the method of construction of the joist, as well as the means for suspending the ceiling structure therefrom will be quite clear after considering the description in connection with the drawings. In fact, the advantages derived from a structure of this kind will be readily apparent to persons skilled in the art to which the invention relates. Therefore, a more lengthy description is thought unnecessary.

Minor changes in shape, size, and arrangement coming within the invention claimed 15 may be resorted to if desired.

Having thus described our invention, what we claim as new is:—

1. As a new product of manufacture, a form insert of the class described comprising 20 a metal strip having rod supporting arms struck out therefrom at longitudinally spaced

points, and disposed at right angles to the body portion, said strip being formed on its lower edge with a depending apertured ceiling suspension ear having a notch in its 25 bottom.

2. A ceiling construction comprising a concrete joist, an insert embedded therein comprising a vertical strip of metal having outstanding supporting arms, reinforcing rods 30 embedded in said joist and resting upon said arms, said inserts being further provided with ears depending below the bottom of the joist, a metal lathing, a backing rod, said rod being engaged with said ear, and means 35 for connecting said rod and lathing with said ear.

In testimony whereof we affix our signatures.

WILLIAM P. KING.
EMMETT T. CORBIN.
